1,972,573

LIFTING JACK WITH TRAVELING PINION
MECHANISM

Leonard D. Nilson, Wayzata, Minn.

Application July 25, 1932, Serial No. 624,623

14 Claims. (Cl. 254—6)

An object of my invention is to provide a lifting jack in which pinion mechanism of simple, durable and inexpensive construction travels along a rack bar to effect raising movement of the lifting head of the jack.

A further object is to provide pawl and ratchet means for rotating the pinion for thus causing it to travel along the rack bar.

Still a further object is to provide hydraulic mechanism including a check valve to prevent lowering of the lifting head with means to release the pawl and ratchet mechanism and open the check valve when it is desired to lower the lifting head.

Still a further object is to provide a jack structure of the character mentioned in the preceding objects with a pawl to prevent settling of the load and to further provide means to release this pawl when it is desired to lower the load.

Another object is to provide a plural ratchet and pawl mechanism having staggered teeth whereby slight movement of the operating handle of the jack will produce lifting movement of the lifting head, this being especially desirable on balloon type tires when they are flat and consequently there is not much room for operating a handle particularly under bumpers, trunk racks, etc. and such possibility of imparting but slight rotation to the ratchet mechanism being thereby accomplished without sacrificing the strength of the teeth of the ratchet member.

A further object is to provide a lifting jack having a pivoted lifting arm with means for swinging the arm comprising a traveling pinion operationally connected with the arm by a link, the pinion being adapted to travel along a rack bar and the link having a roller for maintaining the pinion and rack bar in mesh with each other.

A further object is to provide pawl and ratchet mechanism for rotating the pinion regardless of the length of the stroke imparted to the pawl, such mechanism including a smooth faced ratchet member and wedge face and roller pawl mechanism which will grip the ratchet member in any position instead of merely at predetermined spaced positions as when a toothed ratchet member and a pawl are used.

Still a further object is to provide for the ratchet mechanism of the last object, a hydraulic holding mechanism which will hold any movement gained regardless of how small it is so that even though the operating handle of the jack can move only an eighth of an inch, the jack can be operated at a relatively low speed until the parts of the car prohibiting greater movement of the

operating handle are raised high enough to permit a greater throw thereof.

Still a further object is to provide a ratchet and pawl mechanism which travels with the pinion along the rack bar and an operating handle which also travels with it during the rotation of the pinion.

A further object is to provide means for lowering the jack in the form of a pawl release and an opening device for a check valve included in the hydraulic holding mechanism.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:

Figure 1 is a plan view of a jack embodying my invention.

Figure 2 is a side elevation partly in section of the same.

Figure 3 is a longitudinal vertical sectional view on the line 3—3 of Figure 1.

Figure 4 is a sectional view on the line 4—4 of Figure 1 showing a hydraulic mechanism on an enlarged scale.

Figure 5 is a vertical sectional view on the line 5—5 of Figure 3.

Figure 6 is a plan view of a modified form of construction.

Figure 7 is a side elevation partly in section thereof.

Figure 8 is an enlarged detailed sectional view on the line 8—8 of Figure 6; and

Figure 9 is a similarly enlarged sectional view on the line 9—9 of Figure 7.

On the accompanying drawings, I have used the reference numerals 10 to indicate front wheels. They are mounted on an axle 12 which supports one end of side frame members 14. Side bars 16 are connected with the other ends of the frames 14 and have their rear ends connected with a cross bar 18. The cross bar 18 is supported by swivel wheels 20.

Pivoted at 22 on an upward extension of the side frames 14 is a pair of lifting arms 24. The lifting arms 24 support a pivot pin 26 to which a lifting head 28 is pivoted. The lifting head 28 has arms 30 carrying a pivot pin 32.

Links 34 each have one end pivoted on the pin 32 and one end pivoted on pivot bolts 35. The pivot bolts 35 are mounted on the frame members 14 and the links 34 act as stabilizers for retaining

the head 28 level with respect to the frame of the jack.

For swinging the lifting arm 24 about the pivot 22 and thereby raising the head 28, I provide the following described mechanism. Rack bars 36 are stationarily supported on the frame of the jack. Rotatable pinions 38 are adapted to travel along the rack bars 36. A shaft 40 is provided for the pinions 38 and is secured to them. The shaft 40 rotates in the rearward ends of links 42. The links 42 have their front ends pivoted at 44 to the lifting arms 24.

The links 42 have upward extensions 46 carrying rollers 48. The rollers 48 coat with the upper surfaces of the rack bars 36 to maintain the pinions 38 in mesh therewith. From the construction of the parts just described, it will be obvious that rotation of the pinions 38 will cause them to travel along the rack bars 36 and thus produce swinging movement of the lifting arms 24. For rotating the pinions 38, I provide the following described mechanism.

Pivoted on the shaft 40 is an inverted U-shaped yoke 50 (see Figure 5). The yoke 50 carries a pin 52 on which is mounted a pair of lifting pawls 54. A pair of ratchet wheels 56 is secured to the shaft 40 for coaction with the lifting pawls 54.

Springs 58 normally retain the lifting pawls 54 in mesh with the teeth of the ratchet wheels 56. It will be noted that the teeth of the ratchet wheels 56 are offset relative to each other. The pawls 54, however, are of the same length so that even when the pawls are moved half the distance of the teeth on one ratchet wheel, the pawl 35 of the other ratchet wheel will engage with the teeth thereof and thus step by step rotation of the ratchet wheel can be effected by even a slight oscillation of the yoke 50.

For oscillating the yoke 50, I provide an operating handle 60 pivoted on the pin 52. It is normally locked against pivotal movement relative to the yoke 50, however, by means of a notched segment 62 with which a sliding dog 64 normally coacts. The dog 64 is connected by a link 66 with a release lever 68 and a spring 70 tends to normally retain the dog in coaction with the sector 62. This arrangement provides for adjustment of the operating handle 60 to a vertical or horizontal position or to an intermediate position between the two just mentioned, depending on the clear space for operation of the lever 60 when using the jack on an automobile or other vehicle.

For holding the load lifted by the jack and controlling the lowering thereof without the necessity of oscillating the lever 60, I provide a hydraulic mechanism comprising a cylinder 72 pivoted at 74, a piston 76 therein and a piston rod 78 pivoted at 80. The pivot pin 74 is carried by a cross bar 82 of the jack frame. The pivot pin 80 is carried by the lifting arms 24.

When the lifting head is raised, the piston is extended relative to the cylinder.

The space in the cylinder 72 both in front of and behind the piston 76 is adapted to be substantially filled with oil and during the raising movement, oil from the left end of the cylinder in Figure 2 passes through a port 84 and a bore 86 and then past a check valve 88 into the right end of the cylinder. The check valve 88 will open during the downward oscillation of the operating handle 60 and will close during the upward oscillation thereof to hold whatever lifting movement has been gained.

To guard against any settling of the load when

held by the hydraulic mechanism, I provide holding pawls 90 pivoted on a pin 92. The pin 92 is carried by the links 42.

When it is desired to lower the load, a lowering lever 94 may be engaged and pulled outwardly. The lever 94 is connected by a cable 96 with the pin 92. Suitable pulleys 98 and 100 are provided for the cable 96 to extend over without materially affecting the position of the handle 94 with respect to a lever 102 on the shaft 92 during different positions of the operating handle 60 and the yoke 50. The pulley 98 is carried by the pin 52 which is freely rotatable to assume the position shown in Figure 2.

The pulley 100 is carried by a bracket 104 which is freely rotatable relative to the pinion shaft 40. The edges of the pulleys 98 and 100 over which the cable 96 extends, it will be noted, are substantially at the centers of the pins 52 and 40.

It will be obvious that pulling the lever 94 will swing the pin 92 which will swing an arm 106 thereon and a pin 108 carried by the arm. The pin 108 is adapted to engage lugs 110 of the settling pawls 90 for disengaging them from the ratchet wheels 56. Through the medium of lugs 100 112, links 114 and lugs 116, the lifting pawls 54 may be disengaged after the settling pawls are disengaged.

After such disengagement, the slack in a cable 118 is taken up for swinging arms 120 and 122 105 and pulling a link 124, which in turn rotates a cam member 126. The cam member 126 engages the head 128 of a pin 130 which is slidable in a bore 132 of the piston rod 78. The pin engages the check valve 88 for opening it against the closing action of a spring 134 thereon. Depending on the degree of unseating of the valve 88, the lifting head may be lowered at any desired speed and may be stopped in any position by allowing the valve to close. If desired, springs 115 may be used to assist in returning the lifting arm to its lowered position.

The hydraulic holding mechanism is particularly adapted for a type of ratchet mechanism which will operate even on the smallest of operating handle oscillations.

In Figures 6 to 9 inclusive, I have illustrated a smooth faced ratchet member and wedge face and roller pawl mechanism which may be substituted for the pawl and ratchet mechanism heretofore described and will produce step by step rotation of the pinion regardless of the degree of oscillation of the operating handle. This mechanism is substituted for the pawl and ratchet mechanism of the previous figures and similar parts are given the same reference numeral with the addition of the distinguishing characteristic *a*.

Instead of a toothed ratchet wheel 56, I provide a smooth faced ratchet wheel 56a. The member 56a, however, has ratchet teeth 56b for settling pawls 90a to engage. Instead of holding pawls 54, rollers 54a are provided and they are mounted in a casing 50a, which in turn is connected with the operating handle 60a. Wedge faces 50b are provided between which and the smooth face of the ratchet member 56a, the rollers 54a may be wedged when the handle 60a is swung downwardly and released when it is swung upwardly. Springs 58a tend to wedge the rollers between the faces 50b and the member 56a. The rollers 54a may be released against the action of the springs 58a, however, by a release disk 110a having fingers 110b to engage the rollers when the fingers are rotated clockwise as viewed in Figure 8.

The disk 110a is rotated by a rod 96a pivoted at 97 thereto. The rod 96a has an extension 96b with which a cable 96c is connected. The cable 96c extends under the pulley 100a and rocks 5 the pin 92a to which the settling pawl 90a is secured. A cable 118a extends forwardly, the same as the cable 118, to actuate the hydraulic release mechanism illustrated in Figure 4.

In the first five figures of the drawings, the handle 60 is adjustable relative to the yoke 50. With the type of pawl and ratchet mechanism shown in Figures 6, 7, 8 and 9, this is not necessary inasmuch as the handle can be adjusted to any position desired by merely rotating it 15 around the ratchet member 56a. It can then be oscillated in such position and regardless of how small the strokes of oscillation are, the member 56a will be rotated for causing lifting movement of the jack mechanism and the hydraulic 20 mechanism will effectively hold any lifting movement gained. It will be obvious that other types of gripping mechanisms can be substituted for the type shown in Figure 8 and will operate just as effectively in conjunction with the hydraulic mechanism to act as a holding means and a readily controlled lowering means.

The particular construction shown, it will be noted, is such that at the beginning of the raising operation, the pinions and mechanism carried thereby are at the rear end of the jack 30 frame and out of the way of parts of the automobile which overhang the axles.

As the automobile and consequently such overhanging parts are raised, more room is provided and the traveling mechanism therefore has 35 plenty of room to operate even though traveling toward the front end of the jack.

Some changes may be made in the construction and arrangement of the parts of my device 40 without departing from the real spirit and purpose of my invention, and it is my intention to cover by my claims, any modified forms of structure or use of mechanical equivalents, which may be reasonably included within their scope.

45 I claim as my invention:

1. In a jack structure, a horizontal frame, a lifting member of bell crank shape pivoted thereto, a lifting head carried by one arm of said lifting member, means for imparting pivotal movement to said lifting member comprising a 50 rack stationary relative to said frame and arranged longitudinally thereof, a pinion rotatable therewith, a shaft for said pinion, a link connected with said shaft and with the other arm of said lifting member and means for rotating said pinion.

2. In a jack structure, a horizontal frame, a lifting member of bell crank shape pivoted thereto, a lifting head carried by one arm of said lifting member, means for imparting pivotal movement to said lifting member comprising a rack longitudinally of and stationary relative to said frame, a pinion rotatable therewith, a shaft for said pinion, a link connected with said shaft and with the other arm of said lifting member, means for rotating said pinion and hydraulic mechanism for preventing lowering of said lifting head.

3. In a jack structure, a relatively long, low 70 frame, a lifting member of bell crank shape pivoted thereto, a lifting head carried by one arm of said lifting member, means for imparting pivotal movement to said lifting member comprising a rack stationary relative to said frame and arranged lengthwise thereof, a pinion rotat-

able therewith, a shaft for said pinion, a link connected with said shaft and with the other arm of said lifting member, means for rotating said pinion and hydraulic mechanism for preventing lowering of said lifting head, said hydraulic mechanism including a check valve. 80

4. In a jack structure, a relatively long, low frame, a lifting arm pivoted thereto, a lifting head carried by said lifting arm, means for imparting pivotal movement to said lifting arm comprising a rack stationary and longitudinal relative to said frame, a pinion rotatable therewith and operatively connected with said lifting arm, means for rotating said pinion, hydraulic mechanism for preventing lowering of said lifting head, said hydraulic mechanism including a check valve and means for both opening said check valve and releasing said pinion to permit lowering of said lifting head. 85

5. In a jack structure, a frame, a lifting head raisable relative thereto and means for raising said lifting head comprising a rack bar mounted on said frame, a pinion rotatable along said rack bar and operatively connected with said lifting head to move it when said pinion moves along said rack bar and pawl and ratchet mechanism for rotating said pinion, said mechanism comprising a pair of pawls and a pair of ratchet members having teeth in staggered relation. 90

6. In a jack structure, a lifting head and mechanism for raising said lifting head with step by step movement, said mechanism comprising a smooth faced ratchet member, a pawl member to grip said face regardless of the degree of movement of the pawl member relative to the face and a hydraulic check means to prevent any lowering of said head regardless of any degree it may be raised. 95

7. In a jack structure, a lifting head, mechanism for raising said lifting head with step by step movement, said mechanism comprising a smooth faced ratchet member and a pawl member to grip said face regardless of the degree of movement of the pawl member relative to the face, hydraulic mechanism to prevent lowering of said head and means for releasing both said first mentioned mechanism and releasing said hydraulic mechanism for lowering said lifting head. 100

8. In a jack structure, a lifting head, mechanism for raising said lifting head with step by step movement, said mechanism comprising a smooth faced ratchet member and a pawl member to grip said face regardless of the degree of movement of the pawl member relative to the face, hydraulic mechanism to prevent lowering of said head, a pawl to prevent settling of said head and a single means for releasing said first mentioned mechanism, releasing said hydraulic mechanism and releasing said pawl for lowering said head. 105

9. In a jack structure, a lifting head, mechanism for raising said lifting head with step by step movement, said mechanism comprising a smooth faced ratchet member and a pawl member to grip said face regardless of the degree of movement of the pawl member relative to the face, hydraulic mechanism to prevent lowering and a pawl to prevent settling of said head. 110

10. In a jack structure, a frame, a lifting arm pivoted thereto, a rack bar mounted on said frame, a pinion rotatable along said rack bar, a shaft for said pinion, a link connecting said shaft with said lifting arm, said link having a roller 115

120

125

130

135

140

145

150

thereon for coaction with said rack bar to retain said pinion in mesh therewith and means for rotating said pinion.

11. In a jack structure, a horizontal frame, a lifting arm pivoted thereto, an elongated rack bar mounted lengthwise on said frame, a pinion rotatable along said rack bar, a shaft for said pinion, a thrust link connecting said shaft with said lifting arm, means for rotating said pinion in a direction to raise said lifting arm and hydraulic mechanism to prevent reverse rotation of said pinion.

12. In a jack structure, a frame, a lifting arm pivoted thereto, a rack bar mounted on said frame, a pinion rotatable along said rack bar, a shaft for said pinion, a link connecting said shaft with said lifting arm, means for rotating said pinion in a direction to raise said lifting arm and hydraulic mechanism to prevent reverse rotation of said pinion, said hydraulic mechanism including a check valve and means for rendering the means for rotating said pinion inoperative and opening said check valve to permit the lifting arm to lower.

25.

13. In a jack structure, a frame, a lifting arm pivoted thereto, a rack bar mounted on said frame, a pinion rotatable along said rack bar, a shaft for said pinion, a link connecting said shaft with said lifting arm, means for rotating said pinion, said means comprising a pawl and a ratchet member and hydraulic mechanism to prevent reverse rotation thereof and including a check valve and means for lifting said pawl from said ratchet member and opening said check valve to permit lowering of said lifting arm.

14. In a jack structure, a frame, a lifting head raisable relative thereto and means for raising said lifting head comprising a rack bar mounted on said frame, a pinion rotatable along said rack bar and operatively connected with said lifting head to move it when said pinion moves along said rack bar and pawl and ratchet mechanism for rotating said pinion, said mechanism comprising a pair of pawls and a pair of ratchet members, said pawls and said ratchet members having their teeth in staggered relation to each other.
